UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

CAR-COUPING.

1,213,396.

Specification of Letters Patent.

Patented Jan. 23, 1917.

Application filed January 11, 1916. Serial No. 71,528.

To all whom it may concern:

Be it known that I, ISAAC H. MILLIKEN, a citizen of the United States, residing at Aspinwall, in the county of Allegheny and State of Pennsylvania, have invented certain new and useful Improvements in Car-Couplings; and I do hereby declare the following to be a full, clear, and exact description of the invention, such as will enable others skilled in the art to which it appertains to make and use the same.

My invention relates to the construction of car couplers and especially to those in which the coupler head is pivotally mounted on the coupler stem so as to be capable of lateral swinging movements with respect to the latter. The tendency on the part of some railroads to use heavier coupler heads, heavier knuckles and other coupler parts, consequently results in increasing the length of the coupler head from the pulling face rearwardly to the pivot or connecting pin attaching the head to the stem, thus increasing the ordinary overhang of the head beyond the carry-iron. This greater weight and overhang increases the tendency of the head to droop on the stem, especially as the pivot pin becomes worn from service.

The primary object of the invention is to provide simple, durable and efficient means which are particularly adapted for yieldingly resisting the tendency of long and heavy coupler heads to droop with respect to their stems when the pivots or connecting pins by which these parts are connected become worn as a result of service. This object is accomplished by means which it is practical to so position that they will not interfere with other devices usually mounted on a car adjacent to the coupler, said means being at the same time to a large extent protected against injury and breakage. The means employed also serve to greatly reduce the rate of wear of the pivot pin or connection between the coupler head and stem.

Generally stated, the invention, both in its broad and in its specific aspects, is embodied in a combination involving a coupler head, a coupler stem, means for pivotally connecting said head and stem so as to permit the former to swing laterally with respect to the stem, and means for yieldingly resisting drooping of the head in the direction of the pivotal axis of the latter, said

means for resisting drooping of the head involving a spring mounted on the coupler stem and extending in the direction of length of said stem, and a rigid adjustable connection operatively interposed between the spring and the coupler head.

In the drawings, which illustrate the preferred embodiment of my invention, the scope whereof is pointed out in the claims: Figure 1 is a plan view of a car coupler exhibiting the invention, a portion of the coupler stem being omitted and portions of the car framing being illustrated in order to show the relation of the devices thereto. Fig. 2 is a side elevation of the car coupler illustrated in Fig. 1, neighboring parts of the car structure being shown in vertical section.

The portions of the car structure which are illustrated in the drawings are the center sills, 1, 1, the buffer casting or platform end casting 2, the buffer plate 3, and the foot plate 4. A well known form of carry iron 5, which passes under the coupler stem to afford a support for the coupler is also illustrated. These parts are not features of the invention herein claimed.

6 is the coupler head and 7 is the coupler stem. These parts are pivotally connected so as to permit the coupler head to swing laterally in a horizontal plane, the means for connecting them preferably being a vertically extending bolt or pivot pin 8 which passes through corresponding circular openings in the coupler head 6 and coupler stem 7 in the usual manner.

While I have illustrated a particular form of coupler stem it is to be understood that the specific details thereof as illustrated in the drawing are not material and that the term coupler stem is employed in a generic sense throughout the specification and claims.

Mounted upon the coupler stem 7, preferably upon the upper side thereof, is a coiled spring 9 which at its forward end cooperates with a stop or abutment 10 that is preferably made as a separate casting which is riveted to the coupler stem proper. Between the spring 9 and the spring abutment 10 a washer 11 is preferably interposed. Passing through the spring abutment 10, through the washer 11, and through the interior of the coiled spring 9 is a longitudinally extending inextensible bar or rod 110

12 which bears at its rear end a washer 13 and a nut 14, the spring being interposed between the washers 11 and 13. The forward end of the bar 12 is connected to the 5 upper portion of the coupler head 6 to the rear of the pivot pin 8. For this purpose the part 12 is preferably fashioned with a hook 15 which passes through an eye or opening 16 in a lug 17 that is rigidly, and 10 preferably integrally, attached to the upper face of the coupler head. The opening through the spring abutment 10 is made sufficiently large to permit the rod 12 to move or swing sidewise so as to accommodate 15 itself to the lateral oscillations of the coupler head with respect to the coupler stem. As will be readily understood the operative length of the member 12 which forms the connection between the spring 9 and coupler head 6 may be adjusted by 20 a proper manipulation of the nut 14, the pressure of the spring 9 being thereby also capable of being varied to suit requirements.

The means for preventing drooping of 25 the coupler head, being positioned between the coupler stem and the portion of the car which is above the same, will not interfere with other devices which are commonly mounted upon a car adjacent to the coupler. 30 Moreover, the position of the parts is such that they are not apt to be struck and thereby damaged. Furthermore, the force which prevents the drooping of the coupler head is by these devices applied in such manner 35 that the pressure between the coupler head 6 and the pivot pin 8 is greatly reduced and the wear on the pivot pin is consequently lessened.

What I claim is:

40 1. In a car coupler, the combination with a coupler head, of a coupler stem, means for pivotally connecting said head and stem so as to permit said head to swing laterally with respect to said stem, and spring mechanism extending in the direction of length of the coupler stem and engaging said head to the rear of its pivotal connection with said stem and constituting means for yieldingly resisting drooping of said head in 45 the direction of its pivotal axis.

2. In a car coupler, the combination with a coupler head, of a coupler stem, means for pivotally connecting said head and stem so as to permit said head to swing laterally with respect to said stem, and yielding means engaging the upper portion of the coupler head at a point removed from its axis of pivotal connection with said stem and constituting means extending in the direction of length of said coupler stem for 55 yieldingly resisting drooping of said head.

3. In a car coupler, the combination with a coupler head, of a coupler stem, means for pivotally connecting said head and stem so as to permit said head to swing laterally 60 with respect to said stem, and a spring mounted on said stem and extending in the direction of length thereof, and operatively interposed between said spring and head and serving to yieldingly resist drooping of 65 said head in the direction of its pivotal axis.

4. In a car coupler, the combination with a coupler head, of a coupler stem, means for pivotally connecting said head and stem so as to permit said head to swing laterally 70 with respect to said stem, and means for yieldingly resisting drooping of said head in the direction of its pivotal axis, said means for resisting drooping of the head involving a spring mounted on the exterior 75 of said stem and extending in the direction of length thereof, and a rigid member operatively interposed between said spring and said head.

5. In a car coupler, the combination with 80 a coupler head, of a coupler stem, means for pivotally connecting said head and stem so as to permit said head to swing laterally with respect to said stem, and means for yieldingly resisting drooping of said head 85 in the direction of its pivotal axis, said means for resisting drooping involving a spring mounted upon the upper side of said stem, means for transmitting the resistance of said spring to said coupler head, and means for adjusting the operative length 90 of said last-named means.

In testimony whereof I affix my signature.

ISAAC H. MILLIKEN.
